(57) **CLAIM**

The ornamental design for a machine apparatus for arm function recovery support, as shown and described.

DESCRIPTION

FIG. 1 is a front perspective view of a machine apparatus for arm function recovery support of the present invention;

FIG. 2 is a front view thereof;

FIG. 3 is a top view thereof;

FIG. 4 is a first side view thereof;

FIG. 5 is a second side view thereof;

FIG. 6 is a rear view thereof; and,

FIG. 7 is a bottom view thereof.

The areas bounded by broken lines illustrate the interior portion of the article as distinguished from the exterior thereof and form no part of the claimed design.
